DESIGN FOR AN AUTOMOBILE THERMOMETER

Joseph Fischer, New York, N. Y.

Application September 12, 1940, Serial No. 95,125

Term of patent 3½ years

To all whom it may concern:

Be it known that I, Joseph Fischer, a citizen of the United States, residing at New York city, county of Bronx, and State of New York, have invented a new, original, and ornamental Design for an Automobile Thermometer, of which the following is a specification, reference being had to the accompanying drawing, forming part thereof.

Fig. 1 is a top plan view of an automobile thermometer showing my new design;

Fig. 2 is a front elevational view of the same; and

Fig. 3 is an end view of the same.

I claim:

The ornamental design for an automobile thermometer, as shown.

JOSEPH FISCHER.
